Primary Examiner—Alan P. Douglas*Assistant Examiner*—Lavone D. Tabor*Attorney, Agent, or Firm*—Dougherty & Associates[57] **CLAIM**

The ornamental design for a toothbrush for oral hygiene or the like, as shown and described.

DESCRIPTION

FIG. 1 is a perspective view of a toothbrush for oral hygiene or the like showing my new design with the portion of the handle that is shown in broken lines being for illustrative purposes only and forming no part of the claimed design; FIG. 2 is a top plan view thereof;

FIG. 3 is a right side elevational view thereof;

FIG. 4 is a front elevational view thereof;

FIG. 5 is a rear elevational view thereof;

FIG. 6 is a left side elevational view thereof;

FIG. 7 is a bottom plan view thereof;

FIG. 8 is a perspective view of a second embodiment of the toothbrush with the broken lines forming no part of the claimed design;

FIG. 9 is a top plan view thereof;

FIG. 10 is a right side elevational view thereof;

FIG. 11 is a front elevational view thereof;

FIG. 12 is a rear elevational view thereof;

FIG. 13 is a left side elevational view thereof; and,

FIG. 14 is a bottom plan view thereof.

The bristles are partially shown in FIGS. 3-6 and 10-13 for ease of illustration.
